UNITED STATES PATENT OFFICE.

CLARK F. THAYER, OF JOLIET, ILLINOIS.

COUCH.

SPECIFICATION forming part of Letters Patent No. 660,347, dated October 23, 1900.

Application filed February 28, 1900. Serial No. 6,883. (No model.)

To all whom it may concern:

Be it known that I, CLARK F. THAYER, a citizen of the United States, and a resident of Joliet, in the county of Will and State of Illinois, have invented certain new and useful Improvements in Couches, of which the following is a specification.

This invention relates particularly to couch-bottoms and to the bottoms of chairs and other similar articles, its object being to provide a light strong support for the cushioning-springs—a support that will not stretch and sag, one that is ventilated, and that does not offer lodgment for vermin.

15 In the accompanying drawings, Figure 1 is a plan view of the frame of a couch embodying the features of my invention. Fig. 2 is a longitudinal vertical section through the couch on dotted line 2 of Fig. 1. Fig. 3 is 20 a detail in vertical section, showing the manner of attaching to the side rails the transverse strips of the bottom. Fig. 4 is a detail plan view also showing said means of attachment.

25 Like letters of reference indicate corresponding parts throughout the several views. In the construction of this couch I provide a supporting-framework A, of the usual form, having the side rails A', the end piece A², and 30 the bolster A³. Pieces of band-iron of suitable lengths are provided for the transverse strips B and the longitudinal strips C, said strips preferably being interwoven when in position in the framework A. The ends of 35 the transverse strips B are secured by nails or screws B' to the upper edges of the side rails A' on opposite sides of the supporting-frame A, and staples B², straddling said strips B, are driven into the side rails A' and 40 clenched on the outer sides of said rails. These staples are all in a horizontal plane, and when they are clenched tight each transverse strip of band-iron is drawn taut between its two securing staples. The longitudinal 45 strips of band-iron are woven over and under the transverse strips B and are secured to the tops of the end piece A² and the bolster A³ by nails or screws C' and by staples C² passing through said bolster and said end piece

50 in the same manner as the transverse strips are secured to the side rails A'. Where the transverse strips B and the longitudinal

strips C cross, an opening D through both of said strips provides a means for securing the usual springs to said bottom. Other means 55 for securing the springs may be employed; but this is the way in which I prefer to fasten them. The couch-frame is covered in the usual manner with leather or other suitable materials.

60 While I have described the transverse strips B and the longitudinal strips C as composed of band-iron, I wish it understood that I do not desire thereby to limit myself to the use of this material, as any flexible metallic strip, 65 wire, or strand may be used in the same way and with similar effect.

I claim as my invention—

1. In a bottom for a couch or similar article, in combination, a supporting-frame; flexible pieces for forming said bottom, which pieces are supported upon the top of the supporting-frame and, extending downward on the inner sides of the frame, are drawn taut by means for securing them permanently to 75 each of the inner sides of said supporting-frame; and said securing means.

2. In a bottom for a couch or similar article, in combination, a supporting-frame; flexible pieces for forming said bottom, which 80 pieces are arranged transversely and longitudinally of said couch, the transverse pieces being supported upon the top of the supporting-frame and, extending downward on the inner sides thereof, are drawn taut by means 85 for securing them permanently to each of the inner sides of said supporting-frame; and said securing means.

3. In a bottom for a couch or similar article, in combination, a supporting-frame; flexible pieces for forming said bottom, which pieces are arranged transversely and longitudinally of said couch, the transverse pieces being secured near their ends upon the top of the supporting-frame and, extending downward on the inner sides of the supporting-frame, are drawn taut by staples extending 95 through the sides of the supporting-frame; and said staples.

4. In a bottom for a couch or similar article, in combination, a supporting-frame; flexible pieces for forming said bottom, which pieces are arranged transversely and longitudinally of said couch, said longitudinal

pieces being supported upon fixed transverse portions of said supporting-frame and, extending downward on the inner sides of said transverse portions, are drawn taut by means 5 for securing them permanently to the inner sides of said transverse portions; and said securing means.

5. In a bottom for a couch or similar article, in combination, a supporting-frame; metallic strips for forming said bottom, which strips are arranged transversely and longitudinally of said couch, said transverse strips being secured to the top of the supporting-frame and, extending downward on the inner 10 sides of the frame, are drawn taut by staples extending through said side portions, and which longitudinal strips are drawn taut in a similar manner; and said staples.

15. In a bottom for a couch or similar article,

ele, in combination, a supporting-frame; metallic strips for forming said bottom, which strips are arranged transversely and longitudinally of said couch, said transverse strips being secured near their ends upon the top of the supporting-frame and, extending downward on the inner sides of said supporting-frame, are drawn taut by staples extending through said supporting-frame; staples for said transverse strips and means for securing said longitudinal strips in position, said longitudinal and transverse strips being provided with coinciding openings at the crossing-points of said strips.
